(57) **CLAIM**

We claim the ornamental design for a wristband frame for a fitness monitoring capsule, as shown and described.

DESCRIPTION

FIG. 1 is a top view of a wristband frame for a fitness monitoring capsule; section planes are indicated for FIGS. 9-12.

FIG. 2 is a bottom view of the wristband frame of FIG. 1. FIG. 3 is a left side view of the wristband frame of FIG. 1. FIG. 4 is a right side view of the wristband frame of FIG. 1. FIG. 5 is a rear view of the wristband frame of FIG. 1. FIG. 6 is a front view of the wristband frame of FIG. 1. FIG. 7 is an isometric view of the wristband frame of FIG. 1.

FIG. 8 is a bottom isometric view of the wristband frame of FIG. 1. FIG. 9 is a section view of the wristband frame taken along lines 9-9 in FIG. 1.

FIG. 10 is a section view of the wristband frame taken along lines 10-10 in FIG. 1. FIG. 11 is a section view of the wristband frame taken along lines 11-11 in FIG. 1; and,

FIG. 12 is a section view of the wristband frame taken along lines 12-12 in FIG. 1.

Stipple shading is used in the accompanying Figures to convey surface contouring, not texture. Dash-dot-dash lines are used to indicate section planes in FIG. 1.
